UNITED STATES PATENT OFFICE.

PETER O. HOLMQUIST, OF CHICAGO, ILLINOIS.

CURTAIN-STRETCHER.

1,326,196.

Specification of Letters Patent.

Patented Dec. 30, 1919.

Application filed March 11, 1918. Serial No. 221,591.

To all whom it may concern:

Be it known that I, PETER O. HOLMQUIST, a citizen of the United States, residing at Chicago, in the county of Cook and State of Illinois, have invented certain new and useful Improvements in Curtain-Stretchers, of which the following is a specification.

This invention relates to curtain stretchers and has for its primary object the provision of a novel hinge and connecting bracket for the longitudinal bars of the stretcher whereby the latter may be folded when the stretcher is not in use to permit storage thereof within a minimum space and which will brace and hold the bars rigidly in alignment.

A further object of my invention is the provision of means in a folding curtain stretcher whereby the longitudinal bars may be detachably connected so that their ends substantially abut, thus permitting the pins to be disposed closely adjacent to the ends of the bars.

Further objects and advantages of my invention reside in the combinations herein-after described, as will be better understood by reference to the following specification when read in connection with the accompanying drawing, illustrating the preferred embodiment thereof, in which—

Figure 1 is a front elevation of a curtain stretcher embodying my invention;

Fig. 2 is an edge view of the structure illustrated in Fig. 1;

Fig. 3 is a detail in section through the stretcher on the line 3—3 of Fig. 1;

Fig. 4 is a similar view on the line 4—4 of Fig. 1, and

Fig. 5 is a detail in perspective of the hinge bracket.

Referring to the drawings, 5 indicates a center bar having slots 6 therein to receive pins 7 and fastening bolts 8. The pins 7 provide a pivotal connection between the leaves 9 and 10 of hinge brackets, adapted to receive the ends to the side bars 11 of the curtain stretcher, and brace the hinged brackets and consequently the side bars. The bolts 8 pass through the center bar 5

50 the leaves 9 and the coöperating side bars 11 and top plates 11' and are provided with wing nuts 12, whereby the parts are clamped in assembled relation.

The leaves 9 and 10 of the hinge brackets 55 are preferably stamped from sheet metal and provided with flanges 13 and 14, and

when in operative position the leaves overlie each other as clearly indicated in Fig. 5, with the ends of their flanges 13 and 14 abutting. The leaves 9 and 10 are further 60 provided with flanges 15 and 16 which together with the flanges 13 and 14 embrace the edges of the side bars 11. An inturned integral lug 17 on the hinge leaf 9 is adapted to engage a suitable recess in the coöperating 65 side bar 11 to firmly lock the side bar in assembled relation therewith. A similar lug 18 on the leaf 10 is adapted to enter a slot in the coöperating side bar 11 to prevent lateral movement of the side bar when as- 70 sembled with the hinge leaf. A slot 19 in the edge of the hinge leaf 10 is adapted to embrace the bolt 8 to further stiffen the structure. The end of the side bar 11 co- 75 operating with the hinge leaf 10 is adapted to slip into and out of coöperative relation therewith, and is held in assembled relation by a bolt 20, passing through the side bar 11 and engaging a slot 21 in the edge of the hinge leaf 10. A wing nut 22 on 80 the bolt 20 enables the members to be clamped in assembled relation.

The end bars 23 are provided at their upper ends with plates 24 and 25 secured thereto by rivets 26 extending through the 85 end bars. The plates 25 are provided with inturned ends 27 adapted to engage longitudinal slots 28 in the side bars 11. Bolts 29 extending through the end bars 23 and plates 24 and 25 are provided with wing nuts 30, 90 permit the plates to be drawn together, thus securely clamping the side bars 11. At their lower ends the end bars 23 are provided with hook shaped clamps 31 mounted on bolts 32 which operate in slots 33 in the 95 end bars 23. The hook shaped clamps 31 are provided with inturned ends 34 engaging slots 35 in the lower side bars 11. Wing nuts 36' on the bolts 32 permit the parts to be clamped in assembled relation. The side 100 and end bars 11 and 23 are provided with slots 36 to receive spring pins 37 which engage the fabric to be stretched at intervals throughout the lengths of the respective side and end bars, to hold it in stretched 105 position.

As is indicated in Fig. 1 of the drawing, by reason of the construction described, the side bars 11 at the left of the figure may be readily withdrawn from the hinge brackets 110 by loosening the wing nuts 22 after which the end bar 23 connecting the remaining

side bars 11 may be withdrawn by loosening the wing nuts 30 and 36' and assembled with the first mentioned side bars, thus forming a curtain stretcher of half the normal size 5 and adapted for sash curtains and the like. Upon separation of the end bar 23, the ends of the side bars 11 may again be assembled with the hinge brackets to permit use of the curtain stretcher for full size curtains. The 10 end and side bars 11 and 23 are relatively adjustable by loosening the respective wing nuts to accommodate the stretcher for curtains of different sizes.

The marked advantage of my construction 15 however, is the result of the provision of the hinge brackets comprising the leaves 9 and 10. These hinge brackets permit the side bars 11 to fold upon each other when the stretcher is not in use. Their construction 20 is such that the ends of the side bars are permitted to substantially abut when the stretcher is assembled for use, so that the spring pins 37 may be disposed closely adjacent the joint. This permits the curtain 25 to be held at regularly spaced points and the curtain may thus be uniformly stretched so that no wrinkles appear as necessarily occurs in other forms of folding curtain stretchers, because the pins cannot be placed 30 closely adjacent to the joint between the side bars. The hinge brackets are braced by engagement of the pins 7 with the center bar and hold the side bars firmly in alignment, by reason of the engagement of the 35 flanges 13 and 14 and lugs 17 and 18 therewith so that the stretching of the curtain is uniform throughout. The side bars are readily withdrawn from the hinge brackets by loosening the wing nuts 22 to permit 40 adaptation of the stretcher for small curtains.

From the foregoing it will be readily understood that I have perfected a curtain 45 stretcher, and more particularly a hinge bracket therefor, presenting numerous advantages over similar structures heretofore in use. The improvements embodied in the curtain stretcher herein described facilitates the assemblage and storage of the device 50 which is consequently more useful and desirable than curtain stretchers which do not embody my improvements.

Various changes may be made in the form, 55 arrangement and construction of the parts without departing from the spirit and scope of the invention or sacrificing any of its material advantages, the form hereinbefore described being merely the preferred embodiment thereof.

60 I claim:

1. In a curtain stretcher the combination of a pair of end bars, a pair of side bar sections 65 adjustably connected to one of said end bars, another pair of side bar sections adjustably connected to the other end bar,

a hinge comprising two leaves for each side bar, the corresponding leaves of said hinges being rigidly secured to the inner ends of one pair of side bar sections, means for slidably engaging the other leaves of said 70 hinges to the inner ends of the other pair of side bar sections, and means for detachably securing said other leaves to the other pair of side bar sections, whereby said other pair of side bar sections and the end bar 75 connected therewith may be readily disconnected from the hinges.

2. In a curtain stretcher the combination of a pair of end bars, a pair of side bar sections 80 adjustably connected to one of said end bars, another pair of side bar sections adjustably connected to the other end bar, a hinge comprising two leaves for each side bar, the corresponding leaves of said hinges being rigidly secured to the inner ends of 85 one pair of side bar sections, means for detachably securing the other leaves of said hinges to the inner ends of the other pair of side bar sections, whereby said other pair of side bar sections and the end bar connect- 90 ed therewith may be readily disconnected from the hinges, and a center bar adjustably connected to those leaves of the hinges which are rigidly connected to the side bar sections.

3. In a curtain stretcher, side bars adjustably secured to end bars, each of said side bars comprising two sections, a center bar, and a hinge connecting the adjacent 100 ends of the sections of each side bar and the center bar, said hinge comprising two leaves, a pin pivotally connecting said leaves and engaging the center bar, a rivet fastening one section to one leaf, a bolt detachably connecting the other section to the other 105 leaf, the said other section having a slot to receive said bolt, a top plate overlapping the sections, and a bolt clamping the center bar, the leaves, the sections and the plate together.

4. In a curtain stretcher, side bars adjustably secured to end bars, each of said side bars comprising two sections, a hinge comprising two overlapping leaves pivotally connected, means for fastening the leaves 115 to the sections, flanges at the side edges of the leaves to engage the sides of the sections, and projections on the leaves within the flanges to engage the bottoms of the sections.

5. In a curtain stretcher, side bars adjustably secured to end bars, each of said side bars comprising two sections, a hinge comprising two overlapping leaves pivotally connected, a rivet fastening one leaf to one section, a bolt detachably connecting the 125 other leaf to the other section, flanges on said leaves to engage the edges of the sections, one of said sections having a recess and the other a slot, and projections on said leaves to engage said recess and slot.

6. In a curtain stretcher, an end bar, a pair of side bar sections connected to said end bar, a pair of hinges each having a pair of leaves with one of said leaves rigidly secured to the inner end of one of said sections, the other leaf of each hinge having a projection and a slot, another end bar, a pair of side bar sections connected to said other end bar and having slots in their inner ends to engage the projections on said hinge leaves, and bolts passing through said last mentioned sections and the slots in said leaves to secure said sections rigidly to the leaves and to permit ready disengagement of said sections from the leaves.
